CLAIM

The ornamental design for a beverage maker showerhead as shown and described.

DESCRIPTION

FIG. 1 is a front, bottom perspective view of a beverage maker showerhead showing my design;

FIG. 2 is a top view thereof;

FIG. 3 is a bottom view thereof;

FIG. 4 is a front view thereof;

FIG. 5 is a rear view thereof;

FIG. 6 is a side view thereof;

FIG. 7 is an opposite side view thereof,

FIG. 8 is a front, top perspective view therof, shown in a condition of use; and,

FIG. 9 is a bottom view thereof, shown in a condition of use. The broken lines shown herein are for illustrative purposes only and form no part of the claimed design.
